UNITED STATES PATENT OFFICE.

ANTON JELINEK, OF ELIZABETH, NEW JERSEY.

VIOLIN-BOW.

1,327,433.

Specification of Letters Patent.

Patented Jan. 6, 1920.

Application filed March 29, 1919. Serial No. 286,025.

To all whom it may concern:

Be it known that I, ANTON JELINEK, a citizen of the United States of America, residing at Elizabeth, in the county of Union 5 and State of New Jersey, have invented certain new and useful Improvements in Violin-Bows, of which the following is a specification.

This invention relates to certain new and 10 useful improvements in violin bows or the like and has particular reference to an improved means for detachably fastening the ends of the horsehairs to the ends of bows of this kind whereby an inexperienced person 15 may readily replace broken or worn-out horsehairs from time to time at will as found necessary.

The primary object of the present invention is to so construct the fastening 20 means as to most efficiently and quickly enable the replacement of these horsehairs.

A further object of the invention is to provide fastening means of the present kind which shall be durable and efficient in operation and capable of being cheaply and easily 25 manufactured.

A still further object of the invention is to provide a fastening means of this kind involving a slight modification only of the 30 bows which are now on the market co-operating with adjuncts devised by me.

With the above general objects in view and others that will become apparent as the 35 nature of the invention is better understood, the same consists in the novel form, combination and arrangement of parts hereinafter more fully described, shown in the accompanying drawing and claimed.

In the accompanying drawing, forming 40 part of this specification, wherein like reference characters indicate similar parts throughout the several views,

Figure 1 is an elevational view of a violin bow provided with a fastening means constructed in accordance with the present invention, the intermediate portion of the bow being broken away and one end thereof being shown partially in section,

Fig. 2 is a bottom plan view of the left 50 hand portion of the device shown in Fig. 1,

Fig. 3 is a plan view of the clamping device utilized upon the outer end of the bow and shown detached from the latter,

Fig. 4 is an enlarged longitudinal sec-

tional view of the inner end of the bow illustrating the fastening means for this end of the same,

Fig. 5 is a transverse sectional view taken substantially upon line V—V of Fig. 1,

Fig. 6 is a transverse sectional view taken 60 upon line VI—VI of Fig. 1,

Fig. 7 is a transverse sectional view taken upon line VII—VII of Fig. 4,

Fig. 8 is an enlarged detail view in longitudinal section substantially upon line 65 VIII—VIII of Fig. 9 and illustrating the clamping member and mounting therefor of the fastening device for the inner end of the bow,

Fig. 9 is a top plan view of the device 70 shown in Fig. 8,

Fig. 10 is an enlarged perspective view of the attaching member or slipper for the outer end of the bow with the movable clamping plate thereof removed, and 75

Fig. 11 is an enlarged perspective view of the movable clamping plate of the fastening device for the outer end of the bow.

Referring more in detail to the several views, the present invention provides for 80 the modification of the usual violin bow or the like which comprises the usual staff 5 having an enlarged laterally directed outer end 6 to which the horsehairs 7 are usually fastened in more or less crude and undesirable manners, the nature of which makes it impossible practically for an inexperienced person to fasten these horsehairs in place and to remove the same at will when found necessary for renewal thereof. In order that 90

this fastening may be made quickly and easily by an inexperienced person, I provide the outer end 6 with a socket 8 extending inwardly from the end face thereof as clearly shown in Fig. 1. The end of the laterally projecting portion 6 is provided with a laterally extending toe 9 adapted for reception within the socket formed by the toe portion 10 of the slipper member 11 which is preferably formed of metal to provide a pair of substantially parallel converging flanges 12 adapted for interlocking connection with the end 6 as shown clearly in Fig. 6 so as to retain said slipper 11 in position 95 upon the end 6. The slipper member 11 has an aperture 13 in the sole or base member 14 thereof arranged to coincide with the socket 8 so that the horsehairs 7 may have 100 105

their bound ends inserted into the socket 8 through the aperture 13 as shown in Fig. 1. The end of the laterally projecting portion 6 is also grooved as at 15 for reception 5 of the inwardly extending lug 16 rigid with the end of the base member 14 opposite to the toe portion 10 of the slipper 11, said lug 16 being provided with a threaded aperture 17 whose axis is substantially parallel 10 with the longitudinal axis of the staff 5 and which is adapted for threaded reception of the shank 18 of the adjusting bolt or screw 19. A clamping member 20, preferably formed by stamping from sheet metal is ar- 15 ranged within the slipper 11 upon the base portion 14 and between the flanges 12 there- of, the base 21 of the clamping member be- 20 ing slidably arranged upon the portion 14 between the lug 16 and the toe portion 10. A clamping jaw 22 is provided on the base portion 21 of the clamping member 20 so as to extend inwardly at right angles to said base portion 21, and a flange 23 is formed 25 on the base portion 21 in parallel spaced re- lation to the jaw 22 and provided with a cut-out edge 24 adapted for reception within an annular groove provided around the inner end of the screw 19 so as to provide a swivel connection between the clamping 30 member 20 and said screw 19.

It will be obvious that when the horsehairs are inserted through the aperture 13 into the socket 8 as shown in Fig. 1, said horsehairs will be securely clamped between the 35 jaw 22 of the clamping member and the opposing wall of the socket 8 upon rotation of the screw 19 in the proper direction whereby said clamping member is slid upon the base member 14 of the slipper 11 away 40 from the lug 16. In operation, this clamp- 45 ing of the horsehairs has been found to also produce a flattening or spreading of the same into a uniform ribbon-like arrangement such as is desirable and often found 50 extremely hard to do by means of prior fastening devices. It is also noted that, in practice, the tightening of the clamping member 20 when the horsehairs 7 are taut, also exerts a pull upon the slipper 11 in a 55 direction so as to cause the extension 9 of the end 6 to be forced tightly into the toe portion 10 of said slipper, thereby assisting the flanges 12 in securely and rigidly retaining the slipper in position upon the end 65 of the laterally extending portion 6.

The inner end of the staff 5 is provided with the usual longitudinal bore 25 adapted for reception of the adjusting screw 26 which is operated by the handle 27 to ad- 60 just the frog 28, said adjustment being ef- fected by the threaded engagement of the shank of the screw 26 with the bore of the head 29 which is formed on the screw 30 and which is arranged within the enlarged 65 slot 31 in the adjacent portion of the staff 5,

said screw 30 extending laterally through said slot and being threaded into the frog 28 as shown. The construction of the adjusting means thus far described is substan- 70 tially the same as that of the devices which are at present on the market, the adjust- 75 ment being designed so as to move the frog 28 longitudinally of the staff 5 away from the laterally projecting portion 6 so as to produce a tightening of the horsehairs 7 80 after the latter have been fastened to the end 6 and the frog 28. In order to provide an improved and convenient means for detachably fastening the horsehairs to the frog 28, I provide the screw 30 with a re- 85 duced threaded extension 32 which projects into the chamber 33 provided in the frog 28, said chamber being formed by cutting out the frog so as to provide a shoulder 34 and an inclined surface 35 for purposes which 90 will presently become apparent.

A nut 36 provided with a ball-shaped end 37 is threaded upon the reduced extension 32, said ball-shaped end being retained within the similarly shaped socket 38 of the clamping member 39 by upsetting the latter as at 40 as clearly shown in Fig. 8, whereby 95 said clamping member 39 has a rocking movement relative to the extension 32 and the nut 36. The outer face of the frog 28 is provided with a dove-tail groove 41 for reception of the dove-tail slide 42 so as to close the chamber 33, said slide being pro- 100 vided with a reduced end 43 in spaced relation to the projecting arm 44 of the frog 28, thus forming an entrance opening through which the horsehairs 7 may extend with the free end of the same upon the inclined face 35 within the chamber 33.

It will be seen that, when the nut 36 is 105 threaded upon the extension 32, the end 45 of the clamping member 39 will ultimately come in contact with the shoulder 34, thereby 110 rocking said clamping member upon its mounting 37 and 38 and consequently caus- 115 ing the engaging end 46 of said clamping member to bind the horsehairs against the face 35, thereby also causing a substantial spreading of the horsehairs or a flattening of the same.

When the horsehairs have been clamped in this manner, the slide 42 is positioned so as to close the chamber 33, whereupon a properly shaped ferrule 47 is slid onto the arm 44 of the frog 28 and upon the reduced extension 43 of the slide 42. A wedge 48 is then inserted in the passage formed by the space between the arm 44 and the extension 43 so as to cause a further flattening and spreading of the horsehairs into a ribbon-like form as hereinbefore made mention of in connection with the clamping means at the outer end of the bow 5. The wedge 48 is preferably formed of a flat piece of sheet metal and provided with an angularly 120 125 130

bent end 49 arranged to flatly engage the end face of the arm 44 and thereby provide a finished appearance to the device as clearly shown in Fig. 4, said end 49 serving to also 5 retain the ferrule 47 in position.

From the foregoing description, the fact that ready renewal of the horsehairs may be accomplished by an inexperienced person through the medium of the present invention will be readily appreciated by those skilled in the art, it being noted that the release of the horsehairs can be easily effected by the mere turning of a nut and an adjusting screw respectively indicated at 36 and 10 15 12 in the drawings. If desired, the nut 36 and the head of the screw 19 may be so fashioned as to be readily operated by a key or wrench of the type universally employed in connection with the winding and 20 regulating of clocks.

It is believed that the construction and operation as well as the many desirable advantages of the present invention will be readily understood from the foregoing description, and while the form of the invention herein shown and described is what is believed to be the preferable embodiment thereof, it is nevertheless to be understood that minor changes may be made in the 25 30 form, combination and arrangement of parts without departing from the spirit and scope of the invention as claimed.

What I claim as new is:—

1. In a violin bow, a staff provided with a laterally extending end having a socket therein, said end having an outwardly directed laterally extending toe, a slipper having a toe portion forming a socket for reception of said toe and provided with 35 40 45 flanges in interlocking connection with said end, said slipper having an apertured base portion and being provided with a slidable clamping member in opposed relation to one wall of said socket, and means carried by said slipper for adjusting the clamping member toward and away from said socket wall so as to clamp horsehairs within the socket.

2. In a violin bow, a staff, a frog adjustable longitudinally thereof, means for adjusting said frog including an adjusting screw and an attaching screw having threaded connection with each other, said attaching screw being provided with a reduced threaded extension, said frog having a chamber therein within which said threaded extension projects, said chamber being formed to provide a shoulder and a clamping face at opposite sides of said threaded extension, a nut threaded upon said extension, and a clamping member rockably mounted upon said nut whereby when said nut is threaded onto said extension the clamping member is rocked by engagement of one end of the same with said shoulder

so as to cause the other end thereof to bind horsehairs against the clamping face of the frog chamber.

3. In a violin bow, a staff, a frog adjustable longitudinally thereof, means for adjusting said frog including an adjusting screw and an attaching screw having threaded connection with each other, said attaching screw being provided with a reduced threaded extension, said frog having a chamber therein within which said threaded extension projects, said chamber being formed to provide a shoulder and a clamping face at opposite sides of said threaded extension, a nut threaded upon said extension, a clamping member rockably mounted upon said nut whereby when said nut is threaded onto said extension the clamping member is rocked by engagement of one end of the same with said shoulder so as to cause the other end thereof to bind horsehairs against the clamping face of the frog chamber, a closure plate for the block chamber having an end in spaced relation to a portion of the frog forming an entrance passage for the horsehairs, and means inserted in said passage to cause a flattening of the horsehairs.

4. In a violin bow, a staff having a longitudinal bore in one end thereof and provided with a lateral slot communicating with said bore, an adjusting screw within said bore, an attaching screw fastened within the slot by threaded connection with said adjusting screw, said attaching screw having a threaded shank extending through said slot, a frog slidable longitudinally of said staff and into which said attaching screw shank is threaded, said frog being provided with a chamber, and means including a clamping member rockably mounted on said attaching screw to clamp horsehairs to the frog within said chamber thereof.

5. In a violin bow, a staff, a frog adjustable longitudinally thereof, means for adjusting said frog including an adjusting screw and an attaching screw having threaded connection with each other, said frog having a chamber therein within which said attaching screw projects, said chamber being formed to provide a shoulder and a clamping face at opposite sides of said attaching screw, a member adjustable on said attaching screw, and a clamping member rockably mounted upon the last named member whereby when the latter is adjusted on said attaching screw the clamping member is rocked by engagement of one end of the same with said shoulder so as to cause the other end thereof to bind horsehairs against the clamping face of the frog chamber.

6. A horsehair clamping attachment for the laterally extending ends of violin bows including a slipper having a toe portion and

provided with side flanges, said slipper having an apertured base portion and being provided with a clamping member slideable upon said base portion adjacent the aperture of the latter, and means carried by said slipper for adjusting the clamping member toward and away from said toe portion.

7. In a violin bow, a staff, a frog mounted for movement longitudinally on said staff, 10 adjusting means for said frog including an

attaching screw and an adjusting screw having threaded connection with each other, and means carried by said attaching screw operable to clamp horsehairs to said frog while the frog is operatively disposed on the staff and the attaching screw is operatively associated with said adjusting screw. 15

In testimony whereof I affix my signature.

ANTON JELINEK.
